UNITED STATES PATENT OFFICE.

HARLAND B. GRAHAM, OF SAN JOSE, CALIFORNIA.

FLUID-PRESSURE DEVICE.

Application filed November 17, 1919. Serial No. 338,766.

To all whom it may concern:

Be it known that I, HARLAND B. GRAHAM, a citizen of the United States, residing at San Jose, in the county of Santa Clara and State of California, have invented a new and useful Fluid-Pressure Device, of which the following is a specification.

My invention relates to well pumps. In pumps of the class commonly known to the trade as "inclosed line shaft" turbine pumps, the shaft extends upwardly beyond the end of the tubing and it has been found difficult if not impossible to prevent the fluid in the tubing from leaking out between the shaft and tubing, as such fluid is under considerable pressure. Packing boxes are now in common use to prevent this leakage, but they are unsatisfactory when new, deteriorate rapidly, cause a considerable wear on the shaft, and fail to accomplish the purpose of preventing such leakage. Under such conditions it is common to connect a small pump with the tubing so that the fluid in the tubing may be replenished.

The principal object of my invention is to produce a device of simple form and construction to take the place of the packing boxes now in use for such purpose, which device will prevent the leakage of fluid between the shaft and tubing and at the same time do away with the necessity of having a pump to supply oil to the tubing.

Other objects and advantages will appear hereinafter from the following description and drawings.

Referring to the drawings which are for illustrative purposes only,

Fig. 1 is a vertical sectional view of the upper end of a well showing the head equipped with a device embodying a form of my invention.

Fig. 2 is a sectional plan view on a reduced scale on line 2—2, Fig. 1, and

Fig. 3 is a vertical sectional view on an enlarged scale on line 3—3, Fig. 1.

In the drawings, I have shown my device mounted upon a water pump, the well casing being indicated at 11 and the water column at 12. The pump head 13 is supported upon a concrete block indicated at 14 resting upon the ground, the casing 11 being closed at the top by the concrete and the water column extending through the concrete and threaded into the base 15 of the head.

16 designates the circular side wall of the

head closed at the upper end with a top 17 thereby forming a water chamber 18 which is provided with a water outlet consisting of a discharge pipe 19. Secured to the head 13 by means of suitable bolts 20 is a circular casing 21 provided with a raised floor or horizontal division wall 22 which has a central opening 23 through which extends the upper end of the pump shaft 24, a pulley 25 being fixed to the end of the shaft 24 by means of which the shaft is driven from any suitable power source (not shown). Surrounding the shaft 24 below the top 17 of the head is the oil tube or tubing 26, the upper end of the tube abutting against the underside of the top 17. 28 designates a bushing threaded into the upper end of the tube 26 and into the top 17 of the head.

The space enclosed within the floor 22, 75 the side walls of the casing 21 and the top 17 of the head forms a chamber 29 in which is arranged a circular disk 30 threaded on a threaded portion 31 of the shaft 24 between collars 32 and 33. The disk 30 is of 80 less diameter than the inner walls of the casing 21, leaving a circular passage 35 around the edge of the disk and connecting the upper portion 36 of the chamber above the disk 30 and a lower portion 37 of the 85 chamber below the disk 30.

Mounted upon the upper face of the disk 30 are two radially disposed rotating blades 40 formed of angle iron and secured to the disk by means of headed screw plugs 41. 90 These plugs each have a central bore 42 in which slidably extends a pin 43, the outer end of which is threaded into a radially disposed blade 44 slidably against the under face of the floor 22. The blades 44 are elastically held against the floor 22 by means of coiled springs 45 on each plug 41. Each blade 40 is high enough to extend along the side of its associated plate and together with the plate may be termed a vane which 100 closes the space from the top to the bottom of the upper chamber throughout their length.

The top 17 of the head 13 is provided with stationary blades 47 secured to the top 17 by means of headed plugs 48 which have slidably mounted therein pins 49 which are secured into plates 50 which are elastically held against the disk 30 by means of coiled springs 51.

52 designates a closure ring between the collar 32 and the wall 22 being held in

place by means of screws or bolts 53. 55 designates a pipe having a valve 56 by means of which oil is introduced into the top chamber 36 through an opening 57.

5 The device operates in the following manner:

It is understood that in practice the tubing 26 is filled with oil in which the shaft rotates and that the water in the well is 10 pumped through the water column 12 into the head 13 and thence through the discharge pipe 19. There being pressure on the lower end of the tubing 26, the oil contained therein is forced upwardly and due 15 to such pressure is forced out of the upper end of the tubing 26 between the bushing 28 and the tubing. With my device I prevent this leakage of the oil by placing oil in the chamber above the head until the 20 lower portion 37 is filled with oil and the upper portion 36 is partially filled with oil.

As the pump is operated the shaft and disk 30 thereon revolve in the chamber and the rotating blades 40 with their associated 25 plates 44 whirl the oil in the upper portion 36 of the chamber, which oil is thrown outwardly by centrifugal force thereby building up pressure in the outer circumference of the upper portion 36 and in the passage 30 sage 35 against the oil in the lower portion 37 of the chamber, which in turn places pressure against the upper end of the bushing 28 thereby preventing oil from leaking past the bushing. The oil in the lower portion 35 of the chamber is prevented from taking up the motion of the oil in the upper portion of the chamber by means of the stationary blades 47 and their associated plates 50 mounted on the top 17 of the head.

40 Assuming that the upper portion of the chamber is partly filled with oil, the action of the parts just described causes the fluid, that is, the oil in the upper chamber to fill the outer portion of the upper chamber.

45 It is evident that by getting a pressure on the oil at the outer edge of the disk 30, due to centrifugal force, equal to the pressure of the oil in the tube 26 that there will be no leakage from the tubing into the chamber, 50 assuming that the oil in the lower portion of the chamber is prevented from whirling as above described. The pressure due to centrifugal force at the outer edge of the disk will vary according (but not proportionately) to the distance to which the oil in the upper chamber extends from the edge of the disk toward the center, that is the shaft.

55 Variations in the pressure of the oil in the tubing will simply cause a variation 60 in the distance the oil in the upper chamber extends inwardly toward the shaft, an increase in the pressure in the tubing causing a slight inward movement of the oil in the upper chamber toward the shaft, while a 65 decrease in pressure in the tubing will cause

a slight movement of the oil in the upper chamber outwardly.

If there are bearing surfaces for the shaft within the tubing and the fluid within the tubing is a lubricant, some delivery of fluid 70 into the tubing may be desirable. This can readily be accomplished by introducing oil into the upper chamber near the shaft through the pipe 55 and opening 57 in the wall 22. There being no pressure at such 75 point of introduction, it will be understood that oil so introduced will flow into the upper chamber by gravity. The addition of oil in this manner will increase the column 80 of oil, which in turn will increase the pressure at the outer edge of the disk 30, which in turn will cause a slight movement of the fluid downwardly in the tubing until the 85 pressures are again equal in the outer portion of the upper chamber and in the tubing.

As the pressure on all parts of the under-side of the disk 30 is the maximum pressure obtained on the upper side of the disk at only the outside edge of the same, it is evident that the upward pressure on the disk due to the pressure of the column of oil beneath the disk will be greater than the downward pressure on the disk. This is because the whole under surface of the disk 90 is subject to the maximum pressure while only that portion of the upper surface of the disk at the outside edge of the same is subject to the maximum pressure, the pressure on the upper face of the disk varying 95 from the maximum pressure at the outside edge of the same to zero at the point on the disk to which the column of oil extends inwardly. Such condition results in a force 100 exerted upwardly on the shaft 24 by the plate 30 which force will vary as the pressure in the tubing varies, being greater with a greater pressure in the tubing and less with a smaller pressure, the result being that the load on the bearings in the head 105 of the turbine will be lessened.

What I claim is:—

1. A fluid pressure sealing device comprising a casing, a closed chamber formed in the casing, a rotatable shaft, a disk mounted on the shaft dividing said chamber into an upper and lower portion, said disk being of lesser diameter than the inner wall of the chamber thereby forming a circular passage connecting the upper portion and lower portion of the chamber, and blade means on the disk extending into the upper portion of the chamber into engagement with the walls of said chamber.

2. A fluid pressure sealing device comprising a casing, a closed chamber formed in the casing, a rotatable shaft, a disk mounted on the shaft dividing said chamber into an upper and lower portion, said disk being of lesser diameter than the inner wall of the 130

chamber thereby forming a circular passage connecting the upper portion and lower portion of the chamber, blades on the disk extending into the upper portion of the chamber into engagement with the walls of said chamber, and stationary blades mounted in the lower portion of the chamber.

3. A fluid pressure sealing device comprising a casing having a chamber therein containing fluid, a disk in said chamber dividing the chamber into an upper portion and a lower portion having a connecting passage, and blade means mounted on the upper side of said disk extending into engagement with

15 the walls of the chamber for whirling the fluid in the upper portion of the chamber.

4. A fluid pressure sealing device comprising a casing having a chamber therein containing fluid, a horizontally disposed disk 20 in said chamber dividing the chamber into an upper portion and a lower portion having a connecting passage, radially disposed means on the upper face of said disk in said chamber engaging said disk for whirling the 25 fluid in the upper portion of the chamber, and means for preventing whirling movement of the fluid in the lower portion of the chamber.

5. A fluid pressure sealing device comprising a casing having a chamber therein containing a fluid, a shaft extending into said chamber, a circular disk mounted on said shaft so arranged as to form a circular passage between the disk and walls of the 35 casing, radially disposed blades on said disk engaging the walls of said chamber for imparting a whirling movement to the fluid in the upper portion of the chamber, and radially disposed blades in said chamber engaging said disk for preventing whirling movement of the fluid in the lower portion 40 of the chamber.

6. A fluid pressure sealing device comprising a casing having a chamber therein containing a fluid, a shaft extending into said chamber, a circular disk mounted on said shaft so arranged as to form a circular passage between the disk and walls of the casing, blades secured to the upper face of said disk 50 extending into the upper portion of said chamber, plates resiliently mounted on said disk to engage the top of the chamber and together with their associated plates forming vanes to impart a whirling motion to the fluid in the upper portion of the chamber, stationary plates secured to the bottom of the casing extending into the lower portion 55 of the chamber, and plates resiliently

mounted on the bottom of the casing, which resiliently engage the under face of the disk 60 and together with the stationary blades constitute vanes to prevent whirling motion of the fluid in the lower portion of the chamber.

7. A fluid pressure sealing device for rotary pumps comprising a rotating shaft, a tubing enclosing a portion of the shaft, a casing at the top of the tubing having a chamber formed therein, a disk mounted on the shaft in said chamber leaving a circular 70 passage between the edge of the disk and sides of the chamber, fluid in said tubing and said chamber, means on the disk engaging the walls of said chamber for imparting a whirling movement to the fluid in the 75 chamber above the disk, and means for preventing whirling movement of the fluid in the chamber below the disk.

8. A fluid pressure sealing device for rotary pumps comprising a rotating shaft, a 80 tubing enclosing a portion of the shaft, a casing at the top of the tubing having a chamber formed therein, a disk mounted on the shaft in said chamber leaving a circular 85 passage between the edge of the disk and sides of the chamber, fluid in said tubing and said chamber, means on the disk for imparting a whirling movement to the fluid in the chamber above the disk, means in said chamber engaging said disk for preventing 90 whirling movement of the fluid in the chamber below the disk, and means for delivering fluid to the chamber above the disk.

9. A fluid pressure sealing device for well pumps having an enclosed rotatable line 95 shaft, comprising a tubing enclosing said shaft throughout a portion of its length, a casing at the top of said tubing forming a pressure chamber, a bushing on said shaft threaded into the upper end of said tubing 100 extending into said chamber, a disk in said chamber secured to said shaft, said disk dividing said chamber into an upper portion and a lower portion connected by a circular passage between the edge of the disk and the 105 casing, said tubing and said casing having oil therein, means on the disk for whirling the oil in the upper portion of the chamber, and means in the lower portion of the chamber for preventing whirling of the oil in the 110 lower chamber.

In testimony whereof, I have hereunto set my hand at San Jose, California, this 8th day of November, 1919.

HARLAND B. GRAHAM.
